G. B. SCHEFFY

CLOTH BOARD OR WINDER

Filed Nov. 19, 1925

INVENTOR

GEORGE B. SCHEFFY

BY

J. Granville Myers
ATTORNEY

UNITED STATES PATENT OFFICE.

GEORGE B. SCHEFFEY, OF WEEHAWKEN, NEW JERSEY.

CLOTH BOARD OR WINDER.

Application filed November 19, 1925. Serial No. 70,028.

My invention relates to cloth boards and similar articles upon which various fabrics are wound to form commercial bolts.

An important object of the invention is to provide a very light, strong, rigid and cheap frame of wood or similar material having smooth, flat end faces for satisfactory application of labels and also having smoothly rounded, longitudinal, edge faces to avoid injury to cloth or other fabrics by sharp corners.

Another object is to provide a frame structure which may be composed of wood strips of simple form, these forms being such that the principal shaping operations may be performed rapidly and economically by available high speed wood working machinery. The various parts are usually shaped in long lengths and then cut to shorter lengths and are then adapted for easy and economical assembly to form a frame of the general character described, which provides a smooth and satisfactory surface for suitable covering material (in addition to the end labels) this covering material being usually heavy paper, pulp board, or similar material.

The characteristics and advantages of the invention are further sufficiently explained in connection with the following detail description of the accompanying drawing, which shows one representative embodiment of the invention. After considering this embodiment, persons skilled in the art will understand that many variations may be made within the principles of the invention, and I contemplate the employment of any structures that are properly within the scope of the appended claims.

Fig. 1 is a perspective view of a complete covered and labeled cloth board embodying the invention in one form.

Fig. 2 is a perspective view of the complete frame, uncovered.

Fig. 3 is a section at 3—3, Fig. 2.

Fig. 4 is a section at 4—4, Fig. 2.

Fig. 5 is a fragmentary section at 5—5, Fig. 2.

The frame F, Fig. 2 is composed of various pieces, which are usually wood, since this is the generally available material having the requisite qualities of cheapness, light weight and strength; but other materials may be substituted in some cases if materials are available which have similar characteristics and are capable of being worked econom-

ically for the purpose in view. The frame in the particular embodiment shown consists of side pieces 10, end pieces 11, and one or more cross braces 12. The number of cross braces may be varied in accordance with the length of the frame, the weight and other characteristics of the fabric to be wound upon it, or for other reasons.

The longitudinal edges 13 of the side members are smoothly rounded, leaving flat side faces 14 of substantial width. The inner faces are provided with longitudinal rabbets or grooves 15.

The end members 11 may, in some cases be of two parts but are usually each of integral construction. The outer faces 16 are smooth and flat. A right angled groove or rabbit 17 is made along each inner corner leaving a rib 18 of rectangular section on the inner face. Long strips of this cross section are cut to suitable length and the ribs 18 are then cut to proper length so that their ends enter the grooves 15 of the side members and closely fit therein, leaving portions 20, the full width of the outer portions of the strips, which overlap the ends of the side pieces 13 and are rounded as at 21 to conform to the rounded longitudinal edge formation of the side pieces.

The cross braces 12 (one or more for each cloth board) are cut from long strips of plain, rectangular section and the ends are then formed with tongues 25 adapted to fit closely in grooves 15, and the side members, 90 while the upper and lower faces of the cross braces are flush with the flat side faces 14 of the side members.

The parts may be fitted together entirely by hand or in any suitable jigs, and are sufficiently secured by suitable glue, although the fastening means is not limited to glue, and brads or other fasteners may be employed if necessary or desirable.

The frames are usually covered with a suitable material such as paper, or pulp or straw board of substantial thickness and strength. This cover 31, Fig. 1, is simply wrapped around the longitudinal edges and side faces of the completed frame and secured by an overlapped, glued margin, as at 32. The cover provides a perfectly smooth finish for the board and also fills the openings in the skeleton frame and prevents any contact of the fabric with the sharp inner corners of the frame members.

The flat end faces 16 of the end members

11, provide proper bases for the application of end labels 40, Fig. 1, which may be applied at the cloth board factory or at the textile mills or elsewhere, when the fabrics 5 are wound upon the board. These labels identify the manufacture of the fabric and also usually contain quality, yardage or other designation.

10 End margins of the board may be further finished by paper strips 41 applied over end portions of the cover sheet 31. These surface finishing sheets may in some cases be 15 portions of the labels 40 which are folded over and adhesively secured to edge and side faces of the cover material.

10 The completed board, as is evident from the preceding description, is very light, strong, rigid, and may be produced at low cost. Its light weight is advantageous not 20 only because the weight of the board adds little to the weight of the complete fabric bolt, but because shipping costs from the cloth board factory to the textile mill where the boards are utilized is very materially 25 reduced. The outer surface of the board is entirely smooth, the broad faces being flat and the longitudinal edges smoothly rounded so that any injury to the fabric wound upon it is prevented.

30 I claim:

1. A frame for cloth boards or similar

articles, composed of wood or analogous material, and consisting of side members having smoothly rounded outer longitudinal edges and having grooves on their inner 35 faces, and end members having smooth, flat, outer faces, and ends overlapping the ends of the side members and rounded to conform to the rounded shape of the longitudinal edges of the side members, the end members 40 also having on their inner faces, ribs, the ends of which fit closely and are secured in end portions of the grooves of the side members.

2. A frame for cloth boards and the like, 45 composed of wood or analogous material, and comprising side members having rounded, outer longitudinal edges, and end members having smooth, flat, outer faces adapted for the reception of end labels, said end 50 members having end portions overlapping the ends of the side members to prevent inward displacement, said end portions being rounded to conform to the longitudinal edges 55 of the side members, the side and end members having interfitting tongue and groove formations securing them together.

Signed at New York city in the county of New York and State of New York this 16th day of November, A. D. 1925.

GEORGE B. SCHEFFEY.
